UNITED STATES PATENT OFFICE.

GEORGE MARSHALL, OF FRESNO, CALIFORNIA.

NAIL-STRIPPER.

1,204,678.

Specification of Letters Patent. Patented Nov. 14, 1916.

Application filed October 6, 1915. Serial No. 54,409.

To all whom it may concern:

Be it known that I, GEORGE MARSHALL, a citizen of the United States, and a resident of the city of Fresno, county of Fresno, and 5 State of California, have invented a new and useful improvement in nail-stripers for arranging nails in rows with the heads upward in such position that they can be readily grasped for use.

10 Nail strippers of this character are in general use by box makers and mechanics who drive large quantities of nails.

More in detail my invention relates to the shape of the bottom of the hopper which assists the nails in sliding readily into position, the adjustment of the angle of the runners and hopper to regulate the sliding of the nails, the adjustment of the runners horizontally to receive nails of different 20 sizes, and a stop block so formed that the nail heads will be forced into a position so the head of the outside nail, when grasped by the hand, will be on the top, and other objects which will hereinafter appear.

25 In the drawing accompanying this specification, Figure 1 shows a side view of the box and stripper complete. Fig. 2 is a top view of Fig. 1. Fig. 3 is an enlarged side view of the stop block, showing its relation with 30 the runner. Fig. 4 is a sectional view of the lower part of the runner on the sectional line α . Fig. 5 is a sectional view of the upper part of the runner on sectional line γ . Fig. 6 shows the arrangement of 35 the pieces forming the bottom of the under hopper.

In said drawing 1 represents a box, having a lid 2. When adjusted for use, box 1 is set approximately on a horizontal plane, 40 and lid 2 is opened at right angles to box 1, and is braced in such position by brace 7. This brace is pivoted at one end to lid 2, and the other end contains a slot 72 which is constructed to pass over a pin 73 attached to box 1. Pin 73 is provided with a winged nut 74 whereby brace 7 can be clamped to the box, and by which lid 2 is held in an upright position.

3 is the upper hopper which has a V 50 shaped bottom and ordinary perpendicular sides. In the drawing the bottom is shown with a double V. The bottom can be made with one or more V's, one V being necessary for each runner, hereinafter described. Hopper 3 is attached at the one end to lid 2 by

means of a clamp 82, which is slidably disposed in a slotted member 8 attached to lid 2 in such manner that when the lid is standing upright, the slotted member is vertical.

4 is an under hopper having a V shaped bottom similar to the bottom of the upper hopper 3, except that at the bottom of each V there is a slot 34 extending the entire length of such hopper. I found it better to make each V separate, and with an overlapping portion 12, shown in Fig. 6, to attach it to the adjoining V in case the bottom consists of more than one V. Under hopper 4 is attached to upper hopper 3 under it, and at such an angle that the nails 70 placed therein will readily slide down the length of the V portion of the bottom, and many of the nails in sliding in this manner will fall through the slots with their points downward.

I have formed a set of nail chutes 5 for each V. These chutes are approximately double the length of the bottom of the hopper, and consist of upper runners 5^a and lower runners 5^b, which are hinged together 80 as hereinafter explained. The runners 5^a extend lengthwise under the bottom of the under hopper, are attached thereto, and consists of two parts, 51^a and 52^a, one of which parts is attached to each side of slot 34. The 85 rods forming the parts 51^a and 52^a are shown by a transverse sectional view (see Fig. 5) to be trapezoids, and in assembling them the beveled portions are placed in such relation to each other that the slot formed 90 by them is wider underneath than on the top. In nail strippers now in use the slot in the runners or chutes has the same width on the under side as on the upper side, and when the nails are dropped therein and suspended by their heads they can have no side movement, and in such strippers when two 95 nails are accidentally crossed in the slot, they bind therein. The object of my invention is to untangle the nails which may fall 100 into the slots and slide downwardly therein. This is accomplished by providing a space under the portion of the runners supporting the heads of the nails wherein the nails can swing sidewise while thus suspended. The 105 parts 51^a and 52^a are adjustable horizontally so as to vary the size of the slot, so that different size nails may be used therein. This adjustment is accomplished by having the part 51^a attached to the bottom of hopper 110

115

4 by a bolt and nut, and having the hole through which the bolt passes in 51^a elongated transversely.

The lower runner 5^b consists of two parallel bars 51^b and 52^b which are placed in such relation to each other and to upper runner 5^a that there is a slot of approximately the same width formed, and the slots formed in upper runner 5^a and lower runner 5^b are on a vertical plane, but the slot in lower runner 5^b is under the slot in 5^a, and slightly overlaps it. The lower runner 5^b is hinged to upper runner 5^a in such relation that when a nail slides down the slot in upper runner 5^a, and drops out of the bottom thereof, that it will catch in the slot in under runner 5^b, and the slot is enlarged where the upper and lower runners are joined so the operator can grasp the nails and withdraw them from the slot where the slot is enlarged. For the purpose of hinging the lower runner to the upper runner, and of enlarging the slot at the point of such hinge, I have formed the upper runner 5^a with a bent down portion which is also bent outwardly from the slot, and the under runner 5^b has a bent up portion which is also bent out from the slot, and these bent down and bent up portions are pivoted together preferably with a round bolt and nut so the upper and lower runners can be adjusted either on parallel planes or at an angle to each other.

A cross sectional view of the bars forming under runner 5^b show that they are rectangular, the purpose being to have the slot formed by bars 51^b and 52^b rectangular. This form keeps the nails from piling up in the slot.

The slot formed by bars 51^b and 52^b can be adjusted for large or small nails as hereinafter described.

Under runners 51^b and 52^b are attached at the end opposite the hinge portion to a bar 9 which is placed at right angles to the runners, by a bolt and nut, the bolt passing through an ordinary round hole in the under runners, and through an elongated hole in bar 9 which permits the bars to be adjusted, and clamped in the adjustment desired.

60 6 is a support pivoted to brace 7. It has a plurality of holes of uniform size, 61. One of such supports is at each side of box 1. Bar 9 is reduced at each end to fit into such holes, and is of such length that it will 55 extend from one of such supports to the other. The object of this support and the plurality of holes therein is to adjust the angle of the runners to make the nails slide slowly or quickly.

60 In assembling the stripper for use the lid 2 is opened and clamped at right angles to box 1. Upper hopper 3 is then clamped to the upper part of lid 2 so it extends lengthwise over box 1. Under hopper 4 is attached 65 to the upper hopper at an angle which will

force the nails placed therin to slide therefrom. The runners attached to under hopper 4 are supported at their lower ends by bar 9. Each is then placed in supports 6, and the several parts of the stripper are adjusted so the nails placed in the under hopper will readily slide down the runners with the points hanging downward through the slots in the runners.

In a nail stripper it is desirable to have 75 the nails arranged in the slot in the lower runner 5^b so when grasped between the thumb and first finger and removed from the stripper through the enlarged portion of the slot, that the head of each nail will be 80 below the head of each adjacent nail farther from the point of the fingers. To accomplish this object I have constructed a bumper 10, which I have attached to the lower end of the runners 5, and across the 85 slot therein. This bumper is beveled as shown in Fig. 3, and when the first nail sliding down the runners reaches the bumper its head will ride on such bumper, and the head of such nail will form a sloping 90 surface to guide the next nail head so it will ride upon the last preceding nail which entered the slot, and when the operator removes the nails from the stripper for use they are in the order to use as hereinbefore 95 referred to.

I claim as my invention:

1. In a nail stripper, a hopper having a V shaped bottom and a slot lengthwise in said bottom along the apex of said V, and 100 means for adjusting the slant of said hopper, in combination with runners consisting of an upper and lower section, said upper section being attached to the bottom of said hopper and having a slot therein which registers with the slot in the bottom of the hopper, said upper section extending the entire length of the bottom of said hopper, and slightly beyond such bottom, said upper section having a bent down portion, said 110 lower section having a slot therein on a common vertical plane with the slot in said upper section, and having a bent up portion at one end thereof, the slot in the bent down portion of the upper section being enlarged 115 sufficiently to contain the bent up portion of the said lower section, pivotal hinges connecting said upper section with said lower section at the ends having such bent down portion and bent up portion, means 120 for clamping said upper section and lower section together at any angle at which they may be placed, means for supporting said lower section, and means for adjusting said runners in a slanting position, all substantially as described.

2. In a nail stripper, a hopper having a V shaped bottom and a slot lengthwise in said bottom at the apex of the V therein, a runner constructed with an upper and lower 130

section, said upper section being attached to said bottom, and having a slot therein which registers with the slot in the bottom of said hopper, said slot in the upper section being wider on the under side than on the upper side, said lower section being hinged to the upper section, clamp means to make such lower section rigid with the upper section, said lower section having a slot of the same relative width as the slot in the upper section and having an enlargement of the slot at the hinge portion of said lower section, said lower section being on a plane beneath the upper section and slightly overlapping it, and said slot in the upper and lower sections being on the same vertical plane, a support for the runner at the end thereof opposite said hopper, and means for adjusting the runner at an angle to said bottom, all substantially as described.

3. In a nail stripper, a hopper having a V shaped bottom and a slot lengthwise in said bottom at the apex of said V, a runner consisting of an upper section and a lower section hinged together so that the lower section is on a plane slightly below the plane of the upper section and slightly underlapping it, said upper runner being attached to the bottom of said hopper and having a slot therein which registers with the slot in the bottom of said hopper, and the lower section being constructed of rectangular bars having a bent up portion at the end where they are hinged to said upper section, and placed parallel to form a slot on the same vertical plane as that of the slot in the upper section, and having an enlargement of the slot at the bent up portion of said bars, a support for said runner at the end of the lower section opposite the hopper, means for adjusting the slant of said runner, and means for clamping said runner and hopper in adjusted position, all substantially as described.

4. In a nail stripper, a hopper having a V shaped bottom and a slot lengthwise in said bottom at the apex of the V therein, a runner consisting of an upper section and a lower section hinged together so the lower section is on a plane slightly below and underlapping the plane of the upper section, said upper section being attached to the hopper bottom, and having a slot therein which registers with the slot in the bottom of the hopper, and the lower section extending beyond said bottom, and having a slot therein on a vertical plane with the slot in the upper section, said slot in the upper and lower

sections being approximately of uniform width and having an enlargement of the slot where the upper section and the lower section are hinged together, a support for said lower section at the end thereof opposite the hopper, means for adjusting the slant of the runner and for clamping the runner to such support, in combination with a stop block at the lower end of the slot in such runner consisting of a beveled member attached to the runner at the lower end thereof, in such relation that the plane of the beveled face of said beveled member is at an obtuse angle to the plane of the lower section from the beveled member to the bent up portion at the hinge.

5. In a nail stripper, a box, a lid hinged to said box and adjustable at right angles to the bottom of such box, braces connecting such lid with such box and constructed to be clamped thereto, an upper hopper attached to such lid in such position that it is directly over said box, an under hopper pivoted to such upper hopper, and directly under it, the plane of the bottom of such under hopper being at an angle to the plane of the bottom of the upper hopper, the under hopper having slots in the bottom, runners approximately double the length of the bottom of the under hopper attached to such under hopper, such runners having slots therein which register with the slots in the bottom of the under hopper, such runners having a bent portion so arranged that the slot is the same width at each end of the runner and enlarged at said bent portion, the part of said runner attached to the under hopper being on a higher plane than the part of such runner on the side of the bent portion opposite the hopper, a support for the said runners, means for adjusting the slant of said runners combined, consisting of a bar attached to the lower ends of the runners, a support on each side of the box pivoted to the brace connecting the box and the lid, and means for clamping the support to the brace, said supports containing a row of holes, and said supporting bar having reduced ends to fit within such holes and being of such length that it reaches from the support on the one side to the support on the other side of said box, all substantially as described.

GEORGE MARSHALL.
